CLAIM

We claim the ornamental design for a table base, as shown and described.

DESCRIPTION

FIG. 1 is a front and top perspective view of a table base, according to our new design;

FIG. 2 is a rear and bottom perspective of a table base of FIG. 1;

FIG. 3 is a right side view of a table base of FIG. 1, the left

side view is a mirror image of the right side view of FIG. 3;

FIG. 4 is a top view of a table base of FIG. 1; and,

FIG. 5 is a bottom view of a table base of FIG. 1.

The dashed lines are for purposes of illustrating environmental structure and form no part of the claimed design.
